UNITED STATES PATENT OFFICE.

FREDERICK PERCY FLINT, OF PONDERS END, ENGLAND.

TWO-STROKE INTERNAL-COMBUSTION ENGINE.

1,342,105.

Specification of Letters Patent.

Patented June 1, 1920.

Application filed June 3, 1919. Serial No. 301,505.

To all whom it may concern:

Be it known that I, FREDERICK PERCY FLINT, a subject of the King of England, residing at Ponders End, in the county of 5 Middlesex, England, have invented certain new and useful Improvements in Two-Stroke Internal-Combustion Engines, of which the following is a specification.

This invention relates to two-stroke cycle 10 internal-combustion engines having a working-cylinder and a co-axial compression-cylinder for the charge; and has for its primary object to improve the construction in detail of such engines, particularly with a 15 view to securing simplicity and cheapness in their construction, but also with a view to their satisfactory operation, especially as regards the admission of the charge to the working cylinder.

20 To this end, the invention consists in the construction, arrangement and combination of parts described hereinafter and pointed out in the claims.

One embodiment of the invention and a 25 modification thereof are diagrammatically illustrated by way of example in the accompanying drawing, wherein:—

Figure 1 is a vertical sectional elevation showing one form of two-stroke cycle 30 internal-combustion engine according to the invention, and

Fig. 2 is a detail view in vertical section showing a modified form of passage connecting the admission valve with the working-cylinder.

Like reference characters designate like parts in both the views.

Referring first to Fig. 1, the engine comprises a two-diameter cylinder-casting A 40 securely mounted on a crank-case B in which is journaled a crank-shaft C which is connected by a connecting rod D to the gudgeon-pin E of a duplex piston F.

The cylinder-casting A is made in one 45 piece, having at what will be termed the upper end, a working-cylinder A¹, and at the end adjacent the crank-case B a compression-cylinder A² co-axial with and of larger diameter than the former. A duct A³ is 50 formed in the casting with its length running parallel to the cylinder axis and opening radially inward at its bottom end through a right-angled bend into what is geometrically, though not practically, the 55 cavity of the working-cylinder. The upper

end of this duct opens into a cavity forming an inlet-valve pocket A⁴ from which communication is given to the head of the working-cylinder through a lateral port A⁵. An inlet-valve G is arranged with its major axis parallel to the cylinder axis, a guideway A⁶ for its spindle G¹ being located parallel with, and at a short radial distance from, the duct A³. At its upper end the duct A³ opens into the pocket A⁴ containing a seating A⁷ for the valve G. The lower end of the duct A³ opens radially outward through an outlet which is normally closed by a screw-plug H. As the guideway A⁶ opens into the lower end of the duct A³ at 70 this outlet, the removal of the plug H not only gives access to the duct for cleaning purposes, but also enables a return spring G² of the inlet-valve to be adjusted by means of a ring G³ screwed on the lower end of the spindle G¹. This valve is conveniently automatic, but, if preferred, it may be operated mechanically.

An admission-valve J for the combustible mixture is seated in the flange-like formation occurring at A⁸ where the working-cylinder A¹ merges into the compression-cylinder A², the said flange-like formation being due to the change in diameter in the cylinder-casting A. This admission-valve J is a suction-valve controlled by a spring J¹.

The piston F is constructed as a duplex or differential piston of two diameters, the upper working-piston F¹ corresponding with the working-cylinder and the lower compression-piston F² with the compression-cylinder. The construction is such that the piston F² is of short axial length compared with the piston F¹ and thus has the appearance of being an axial extension of a flange upon the latter. Both pistons are provided with grooves for rings, and in the body or trunk of the working-piston F¹ a cavity or recess F³ is formed just above the upper face of the compression-piston F². This cavity is so situated as to register with the open inwardly-directed end of the aforesaid right-angled bend of the duct A³, the registering position being, as will be obvious, that 95 when the working-piston F¹ is most fully advanced into and inclosed by its cylinder.

The crank-case B is secured by means not shown in the drawing to the lower open end of the compression-cylinder A²; it contains 105 the balanced crank constituting a flywheel,

and, to one side of the latter, an exhaust-valve operating cam K keyed on the shaft C. The crank-case is divided into two halves at B¹ in a plane containing the plane of oscillation of the connecting-rod D, and in the half on the same side as the cam K is an oil-pump shown at L. This pump comprises a cylinder B² formed integral with the crank-case, and a spring-controlled plunger L¹ which is operated by direct engagement with the cam K. The lower end of the plunger is hollow and is fitted at its lower end with a non-return valve L² so as to form a "bucket." A similar non-return valve L³ is fitted in the bottom of the pump cylinder B² and controls a duct opening into the bottom of the crank-case, through which oil flows to the pump. When the pump is operated, the oil is delivered by way of a port in the plunger midway along its length to an outlet B³ in the crank-case, this outlet being connected by conduits, not shown, to the parts of the engine requiring lubrication.

25 A spring-controlled exhaust-valve M controlling an exhaust-passage M¹ in the wall of the cylinder A¹ is provided diametrically opposite the inlet-valve G, but has its seating A⁹ farther away, measured along the axis of the engine, from the axis of the crank-shaft than is the inlet-valve. The spindle M² of the exhaust-valve is guided in a long guide N mounted in the wall of the exhaust way M¹ and is guided through the medium of an intermediate rod O by the tappet P. The intermediate rod O slides in lugs cast on the cylinder-casting, and the tappet P is housed in a bearing P¹ in the crank-case B and is operated by the cam K.

30 In addition to the exhaust-valve M a lateral exhaust-port A¹⁰ is provided in the cylinder wall so as to be covered and uncovered by the piston F¹ in the well-known manner.

45 An internally threaded bushing Q is provided, as usual, in the head of the cylinder A¹ for the reception of a sparking plug. Threaded caps R and R¹ are also provided in apertures in the cylinder casting to give access to the inlet-valve G and the exhaust-valve M, respectively.

50 In the modified construction shown in Fig. 2, an annular pocket A¹¹, not however formed as a complete ring, is formed in the upper portion of the wall of the working-cylinder A¹ and is connected with an auxiliary supply duct A¹² which is controlled at its one end by a second inlet-valve G¹ and is connected at its other end to the duct A³. The subsidiary pocket A¹¹ opens into the working-cylinder A¹ by way of ports A¹³. These ports are situated farther inward in the direction of the stroke of the engine than is the port A⁵ controlled by the valve G. Owing to the described position of these

ports A¹³ they are covered and uncovered by the piston F¹ sooner and later, respectively, than is the port A⁵, when the piston moves inward and outward in the cylinder A¹. The subsidiary pocket therefore serves 70 to afford a kind of reservoir of combustible mixture, its object being to increase the supply of fuel to the working-cylinder during the expansion stroke as compared with the amount that can be delivered to it at the 75 commencement of the expansion stroke by the ordinary means.

The volume of the compression-cylinder A² swept out by its piston F² is so dimensioned as to take account not only of the 80 volume of the working-cylinder A¹ and its piston F¹, but also of the duct A³ and, in the event of a subsidiary pocket A¹¹ being provided, of the duct A¹², but the volume swept out in the compression-cylinder is obviously so chosen as to give the required ultimate compression in the working-cylinder. 85

It will be appreciated that the cavity F³ and the co-operating duct A³ are simply to construct and provide, since both may be 90 formed directly in the body and its respective part in the process of casting the part. Moreover the masking of the inlet port by the piston in the working-cylinder affords a simple additional safeguard to prevent ignition being communicated to the charge in the compression-cylinder. 95

What I claim as my invention and desire to secure by Letters Patent is:—

1. In a two-stroke cycle internal-combustion engine of the character described, the combination of a two-diameter cylinder comprising a working-cylinder having an exhaust port, and a compression-cylinder which is co-axial with the working-cylinder 100 and has an admission port, a duplex piston comprising a working-piston movable in the said working-cylinder and a compression-piston movable in the said compression-cylinder, the wall of the working-cylinder being provided with a fuel-supply duct whereof its supply end opens into the end of the working-cylinder adjacent to the compression-cylinder and is normally closed by the said working-piston, and whereof its delivery end opens through an inlet port into the end of the working-cylinder remote from the compression-cylinder and a valve arranged to control the delivery end of said duct, the trunk of said working-piston being provided 110 with a cavity so arranged as to periodically establish communication between the supply end of the said duct and the compression-cylinder when the duplex piston is reciprocated, the said inlet port and the exhaust port of the working-cylinder being located on opposite sides of the working-cylinder and so situated in the axial direction thereof that when the working-piston 120 is near the end of its instroke, the said in- 115

125

130

let port is covered by the working-piston, but the exhaust port is never thus covered, for the purpose specified.

2. In a two-stroke cycle internal-combustion engine of the character described, the combination of a two-diameter cylinder comprising a working-cylinder having an exhaust port and a compression-cylinder which is co-axial with the working-cylinder and has an admission-port, a duplex piston comprising a working-piston movable in the said working-cylinder and a compression-piston movable in the said compression-cylinder, the wall of the working-cylinder being provided with a fuel-supply duct whereof its supply end opens into the end of the working-cylinder adjacent to the compression-cylinder and is normally closed by the said working-piston, and whereof its delivery end opens into the end of the working-cylinder remote from the compression-cylinder, a

valve arranged to control the delivery end of said duct, the wall of the working-cylinder being also provided with a pocket which is connected by an auxiliary duct with the fuel-supply duct and opens into the working-cylinder by way of ports which are situated between the delivery end of the said fuel-supply duct and the end of the working-cylinder adjacent to the compression-cylinder, and a valve arranged to control the communication between said pocket and said auxiliary duct, the trunk of said working-piston being provided with a cavity so arranged as to periodically establish communication between the supply end of the fuel-supply duct and the compression-cylinder when the duplex piston is reciprocated, for the purpose specified.

In testimony whereof I affix my signature. 40

FREDERICK PERCY FLINT.
